EARLIEG NEIL VAN NOSTRAND, OF FLUSHING, NEW YORK, ASSIGNEE TO TELAUTOGRAPH CORPORATION, OF NEW YORK, N. Y., A CORPORATION OF VIRGINIA.

TELAUTOGRAPH SYSTEM.

Original application filed May 26, 1925, Serial No. 32,905. Divided and this application filed June 30, 1926. Serial No. 119,628.

This invention relates to improvements in telautograph systems, and particularly to a paper-shifting mechanism therefor.

The present application is a division of my application Serial No. 32,905 filed May 26, 1925.

The object of this invention is to provide a paper-shifter which will be reliable in operation and which will not only serve to feed the paper record strip at the receiver, but which will close the circuits for the field-magnets and for the pen lifter magnet.

The invention will be described more specifically in connection with the accompanying drawings, showing a paper strip feeding mechanism for telautographs embodying the invention.

In the drawings:—

Figure 1 is an elevation, partly in section, showing the plungers or cores in their retracted position, the circuit for energizing the coils being merely diagrammatic.

Figure 2 is a sectional view at right angles to Figure 1.

Figure 3 is a detail view of the armature and its attached parts.

Figure 4 is a detail perspective view of a spring switch device which may be operated by an electro-magnet device embodying the invention, and

Figure 5 is a diagrammatic view illustrating the circuits of a telautograph receiver in which the invention is used.

In the preferred embodiment of the invention, two solenoid coils A, A', are employed, each of which is arranged to be energized by an electric current. In the present example, the coils are included, in series, in an electric circuit, which may be energized from any suitable source. For the present purposes of explanation the circuit is shown in Figure 1 as a simple circuit arranged to be opened and closed by a switch 1, this circuit including a battery 2.

Each of the coils, A, A', is mounted on a tube 3, 3' of suitable material, preferably non-magnetic. In practice, tubes of brass are employed. Within these tubes, the solenoid cores or plungers, B, B', can slide in the direction of their longitudinal axes. Each core has one end tapered, as will be clear from the drawings. The slope and length of this tapered portion is of consider-

able importance. The length of the tapered portion must be greater than the desired stroke of the cores. Also it must not be less than the maximum diameter of the core and not more than 1½ times said diameter. The slope should not be substantially less than 5 degrees nor more than 15 degrees.

The two cores or plungers are longer than their coils and have their respective outside ends connected by an armature C whose cross sectional area is sufficient to give a path of good permeance for the flux, while at the same time the cross-section is relatively thin in the direction of the longitudinal axes of the cores. Therefore, to obtain the desired cross-sectional area, the armature is made relatively wide, its width being greater than the diameter of the cores and its thickness less.

Where the electro-magnet device is used to shift a strip of material the armature C may be provided with a shunt magnetic circuit having an air gap, the arms of the shunt, in the example illustrated, being indicated at 4, 4', with an air gap at 5. This shunt magnetic circuit with a gap may be used to actuate a subsidiary armature of magnetic material, as for example, a clamping armature indicated at D, which may be used to clamp the strip material so that, as the plungers move, the strip material will be moved with them. As shown in the present example, the clamping armature D consists of a disk supported on a pin 6 passing through the center of the disk, this pin being carried by a guide-bar 7 attached to and extending above a guide-plate 8 secured to armature C. The guide bar is recessed to receive the disk, as will be clear from Figure 3. The guide-plate and guide-bar are made of non-magnetic material and are arranged to provide a guide-slot 9 between them, through which the material to be fed or advanced may pass. In the best embodiment of the invention, the guide-plate 8 is of metal having a co-efficient of expansion the same as that of the armature. In practice it has been found that Monel metal most nearly meets the requirements. Thus any warping of the plate due to thermal changes is avoided. The clamping armature D will serve to clamp the strip of material against the poles 4, 4', when the armature C is energized, and to release the strip when said

armature is de-energized, thereby allowing the armature C to move without moving the strip of material.

For ease in introducing the strip of material through the guide slot 9, the guide plate 8 may be provided with a guide lip 8' arranged at an angle, as shown in Figure 2. In this view the dotted line Z indicates the strip, which in a telautograph will be a strip 10 of paper leading from a suitable roll, not shown, and assumed to be advanced in the direction of the arrow z, Figure 2. It is convenient, also to so mount the disk, D, that in its non-energized position, it will tend to 15 assume an inclined position, as indicated in Figure 2, thus making it easier to insert the end of a strip of paper through the guide slot 9. To accomplish this result, the disk may have its central opening which receives 20 the supporting pin countersunk on its side facing the armature so that when released by the armature, the weight of the disk will tend to tip it to the desired incline. Furthermore, owing to this incline 25 the edge of the disk nearest to the paper comes into contact with it first when the disk is drawn up and thereafter the disk swings into full bearing on the papers so there is no sudden slam of the disk against the paper, 30 and consequently no noise in clamping the paper.

The electro-magnet device also comprises a yoke E which is provided with openings, one for each plunger, into which openings 35 the inner ends of the respective plungers may move, the said openings being in alignment with the plungers.

The yoke has a cross-sectional area, intermediate the openings, which is not less than 40 the maximum cross-sectional area of the requisite plunger made of material of high permeability and in practice may be and advantageously is from $1\frac{1}{2}$ to 2 times that of such a plunger.

45 Furthermore, that dimension of the cross-section of the yoke which extends parallel to the longitudinal axis of the plungers is at least as great as the diameter of such a plunger, and advantageously is greater. In 50 practice it has been found that said dimension may be from 1 to $1\frac{1}{8}$ or $1\frac{1}{2}$ times the maximum diameter of such a plunger. By making that dimension of the yoke which extends in a direction parallel to the longitudinal 55 axis of the plunger, of a size not less than the maximum diameter of such a plunger, B or B', and tapering the plunger ends to a sufficient extent, while also arranging them to move into the openings in the 60 yoke, an important effect on the action of the plungers is obtained, in that a longer stroke is made possible by keeping up a strong pull until toward the end of the inward stroke of the plungers, whereupon the 65 pull rapidly decreases until at the end of

the stroke the remaining pull is only sufficient to hold the plungers stationary.

In order to limit the movement of the plunger and armature C, a suitable means for limiting the play of the plungers within 70 their coils is provided. In the direction in which the plungers move when drawn into the coils, their motion is limited by a yielding stop means. In the present example, this comprises a pad 10 of felt which rests 75 upon the armature and has such a thickness that when compressed between the ends of the bobbins and the armature it will stop the plungers at the desired inward position. An advantage of this yielding material is 80 that it is noiseless.

The motion of the plungers in the opposite or outward direction is limited by a suitable stop mechanism. In the best embodiment of the invention this stop mechanism is adjustable. It comprises a single rod 11 screw threaded into the yoke E, the rod extending through the armature and guide-plate and being provided with a head 12 outside the guide plate. By means of the head, the rod 11 may be turned to screw it in or out with relation to the yoke E. There may be a locking screw 13 provided in the yoke to engage and lock the rod 11.

In the best embodiment of the invention 95 the side of the guide-plate next to the head of the rod 11 carries a projection, such as a boss 14, through which the rod 11 passes, this boss being of non-magnetic material and secured to the guide-plate, as for example, 100 by soldering or riveting or both. The outer side of the boss 14 is provided with a recess which, advantageously, has its inner wall coned. The rod 11 is provided, next to its head, with one or more washers 15 of yielding material arranged to be squeezed between the head 12 and the coned walls of the boss 14, thereby stopping the plungers and armature.

In the best embodiment of the invention 110 the rod 11 is so located that its longitudinal axis coincides with the longitudinal axis through the center of gravity of the plungers and armature, so that when the plungers and armature are stopped in their outward 115 movement by the head 12 of the rod, there will be no tendency of the plungers to swing laterally in their respective tubes 3, 3'.

The electro-magnet device may be provided with means for supporting it in a suitable manner. In the example shown, the yoke is carried by an arm F extending from a plate f, which may be secured to a suitable wall, post or the like, as for example, the slab of slate or the like indicated at G. The arm F may be integral with the yoke and may have reinforcing ribs, as indicated at f¹, and also may have a centrally arranged bracing web or flange f².

This web or flange serves not only to brace the arm F from the plate f, but also serves as a support for a contact device to be operated by the electro-magnet device 5 if desired, as more fully explained herein-after.

It will be noted that the apparatus is so constructed that even in their extreme outward position, the plungers B, B', extend 10 through the coils for substantially the entire length of each coil, so that when the coils are energized there is a strong magnetic pull and, because of the relatively great 15 depth or thickness of the yoke and the slope and length of taper of the core ends the pull on the plungers is maintained nearly uniform until the inner ends of the plungers approach the outer face of the yoke, whereupon the pull falls rapidly so that when the 20 plungers are stopped at the end of their inward stroke, the remaining pull of the plungers is just sufficient to hold them in place. In the embodiment of the invention shown in the drawings, the plungers are 25 assumed to be vertical, and with such an arrangement, they would move outward—that is, downward—by gravity. In such an arrangement of the apparatus, the remaining pull of the plungers at their extreme upward 30 position is sufficient to overcome the action of gravity on the plungers and their attached parts.

In practice, the plungers are stopped 35 slightly before their inner, or upper, ends reach the plane of the outer or upper face of the yoke. It will be observed that because of the solid armature connection between the two outer ends of the plungers a good magnetic circuit is provided, the 40 magnetic circuit being closed at all points except between the inner ends of the plungers and the yoke, so that by the proper taper of the plunger ends and by the use of a deep yoke, the desired results are obtained.

45 When the electro-magnet device embodying the invention is used as a paper-shifter for telautographs, the coils A, A', are included in a local circuit, which may be closed by a relay in one of writing line circuits, so that a strong current may be supplied to energize the said coils A, A', thus giving a relatively powerful stroke for feeding the paper strip.

With such an electro-magnet device, it 50 becomes possible to use the paper shifter magnets to operate certain contact devices for closing and opening other circuits of the telautograph system. The advantage of this is that the momentum of the plungers and 55 their attached parts insures the proper action of the circuit closer and allows them to be made more rugged than where only a light relay is used.

In an apparatus embodying this feature 60 of the invention the armature is provided

with a post 16 carrying a roller 17 which may be revolvably mounted on a pin 18, in the present example shown as a screw which is threaded into the post. The roller 17 is arranged to be forced between a pair of 70 outwardly flared or sloping jaws 19, 19', each carried by a central spring H, H'. These springs may be secured to, but insulated from, the web or flange f². The electric circuit to be closed and opened at the 75 contact springs has its terminals connected to the respective contact springs. When the electro-magnet device is energized the roller 17, which is of conductive material, enters between and makes contact with the 80 jaws 19, 19', of the two springs H, H', thereby closing the circuit. At the same time, the tension of said springs is sufficient to cause some friction against the roller 17 thereby assisting in checking the inward 85 movement of the solenoid plungers B, B'. Thus the contact springs serve as brakes as well as circuit closing devices.

In the embodiment of the invention illustrated in the drawings, two circuits may be 90 controlled at the contact device. Where this is to be done, the flange f² supports a third contact spring K and a rigid abutment device or stop L, these being insulated from the other springs. The contact spring K and 95 the contact spring H may each be provided with contact points 20, 21, Figure 5, which contact with each other when the spring H is forced outward by the roller 17. The end of the spring K has its motion in the direction toward the spring H limited by suitable means. In the present example, this result is obtained by providing a curved or hooked end 22 to the spring K, into which the end 100 of the abutment device L projects. This 105 abutment device, although of rigid material, may be bent, more or less, to adjust it and thereby to adjust the field of play of the spring K. The result of this construction is that the spring H may have a relatively 110 light tension against the roller 17 as the latter first contacts with the inclined jaw 19 and then as the spring H is moved further in a lateral direction it comes into contact with and pushes laterally the spring K, 115 thereby effectively closing the electric contact between H and K while at the same time the springs H and K may have a further outward movement together, so that they 120 can yield as the roller 17 travels further between the spring jaws 19 and 19'. This avoids the necessity for extremely accurate adjustment of the springs. When the electro-magnet device is de-energized, the plungers B, B' and their attached parts 125 move outward, thus removing the roller 17 from between the jaws 19, 19'. The spring H moves back, by its own resiliency, toward the spring H', the spring K following spring H for a short distance, until stopped by its 130

hooked end 22 engaging the stop L, whereupon it is no longer able to follow the spring H and the latter, in its further movement, causes a separation of the contacts 20 and 5 21, thereby breaking the electric circuit from K to H.

In Figure 5 is illustrated diagrammatically the circuits of a telautograph receiver in which the hereinbefore described electro-magnet device is arranged not only as a 10 paper shifter, but also to close two circuits, viz., the field magnet circuit and the pen lifting circuit. Referring to Figure 5, W¹ and W² indicate the two writing lines of the 15 receiver which are intended to receive variable currents over the line wires from the transmitter, the strength of the currents varying in accordance with the position of the transmitter stylus. The writing line W¹ 20 contains, as usual, the resistance coil indicated at 23 and the movable bucket coil 24. The writing line W² also contains the usual resistance coil 23' and the movable bucket coil 24'. In addition, it contains the winding 25 of a relay having an armature 26 arranged to close against a contact 27. At X is indicated the positive wire of the power circuit which connects to two branches x¹ and x², the former containing the windings 30 A, A', of the paper shifting mechanism hereinbefore described. The branch x¹ also includes the contact 27 and the armature 26 of the relay. When the relay is energized by a current passing in the line W², the relay 35 armature closes against the contact 27 and current from the power line flows over the branch x¹ and energizes the winding A, A', of the paper shifter. The branch x² contains the field magnet windings 29, 29', and 40 has a terminal connected to the spring H' of the contact device operated by the paper shifter, as hereinbefore described. At P is indicated the incoming pen-lifting line connected to the line P', which includes the 45 winding 32 of the pen lifter magnet. This line P' extends to the spring K of the contact device carried by the paper shifting mechanism, the spring H of which is connected by the wire p', to the negative lead 50 Y. When the contact springs K and H are out of engagement with each other, pen-lifting lines P, P' stand open at said springs. A shunt p is provided around the windings 55 32 of the pen-lifting magnet and around the contact springs K and H. In this shunt is included the winding 33 of the high resistance signal buzzer. The lines W¹, W², x¹ are extended to and connected directly to the negative line Y of the power circuit. 60 The branch x² of the positive power line is connected to the negative line Y through a resistance 30 and a condenser 31 which permit the passage of discharge oscillations and thereby reduce or prevent any sparkling at 65 the spring H' when the circuit is open at

said spring by the withdrawal of the roller 17 from the jaws of the two springs H' and H. The operation of the apparatus is obvious from the diagram but may be briefly described as follows:

When the receiver is receiving a message, writing currents of variable amperage flow over the wires W¹ and W² to the negative wire Y and return to the transmitting station either over a line wire or through a ground, as indicated at Y². When the current flows through the writing line W² it energizes the winding 25 of the relay and closes the branch circuit x¹ from the positive power line X to the negative power line Y, thereby energizing the winding A, A', of the electro-magnet device shown in Figure 1. The plungers B, B', are drawn inward and the paper clamping disk D is simultaneously attracted to clamp the paper strip, which is pulled along by the movement of the armature C and plungers B, B'. Also, the roller 17 contacts with the jaws 19, 19', thereby closing the electric circuit through the springs H, H', and moving the spring H 90 into contact with the spring K, thus closing the circuit through the lines P, P' and also connecting the branch line x² to the negative power line Y, through the wire P' whereby the field magnet windings 29, 29', are 95 energized so that the variable currents in the bucket coils 24, 24', will cause said coils to move in the field and thereby operate the pen arms in the usual way. With the pen-lifter lines P, P', closed at the springs K 100 and H, any current coming over the line P from the transmitting station will energize the winding 32 of the pen lifting magnet and cause its armature to be lifted. When no current comes over this line P the winding 32 is de-energized and the pen-lifting magnet releases its armature to lower the writing pen against the paper.

When no current flows over the writing line W², the winding 25 of the relay is de-energized and the relay armature 26 opens the branch circuit x¹, thereby de-energizing the windings A and A' of the paper shifting mechanism. The plungers B, B' are released and moved outward, thereby moving the roller 17 away from engagement with the jaws of springs H, H', and allowing the springs H to separate from the spring K. When the roller 17 moves out of contact with either spring H or H' the branch x² of the power line is opened and the field windings 29, 29', are de-energized. The separation of springs H and K opens the lines P, P'. If in this condition of the apparatus, a signalling current is sent over the line P, this current will pass over the shunt p and will serve to operate the signal buzzer whose winding is indicated at 33. The lines X and Y may be connected to line wires leading to the transmitter, in 130

which case the ground Y^2 is unnecessary, or said wires X and Y may be connected in a local power circuit in which case the ground Y^2 is necessary in order to allow to writing 5 currents in the wires W^1 , W^2 , and the signalling current or pen lifting current in the wires p and P , P' , to return to the transmitting station through the ground. As before stated, the branch containing the 10 resistance 30 and condenser 31 is merely to take care of the oscillating discharge around the spring H' when the circuit is broken between said spring and the roller 17.

By using the line relay in the line W^2 15 merely for the purpose of closing the branch x^1 of the power line through the windings A , A' , of the paper shifting mechanism, the relay device is greatly simplified over the structures heretofore employed, in which 20 the said relay was used, not only to close the circuit through the paper shifting windings, but also to close the circuit through the field windings and through the pen lifter windings. As this relay is, of necessity, operable 25 by weak currents, it is very difficult to adjust properly, when employed to operate more than one set of contacts. By the present construction, the paper shifter, which is 30 a relatively rugged and powerful device, is used to close the respective circuits through the field windings and through the pen lifting windings.

It will be noted that in the embodiment 35 of the invention shown in the drawings the means for limiting the play of the plungers is so adjusted that in the extreme outward position the faces of their tapering ends lie substantially in the same plane as the inner face of the yoke, or, at least, of that part of 40 the yoke in the vicinity of the coils. Hence, the maximum power is applied to the plungers at starting, due to the concentration 45 of the magnetic flux at the tapered ends of the plungers and at the inner face of the yoke adjacent the openings therein. At this position the square of the flux density divided by the equivalent area of the path is a maximum.

An important difference between this electro-magnet device and plunger and solenoid devices heretofore employed is that the latter 50 applies the maximum pull on the plungers just beyond the center of the winding, whereas the present device applies its maximum power at a point in the plane of the 55 extreme outer end of the winding. Also, it is to be noted that the main armature plays an effective part when the plungers are in or approaching their innermost position.

60 What is claimed is:

1. In an electro-magnet device, the combination, with a pair of plungers, a yoke having openings to receive said plungers, and a main armature secured to both plungers and formed to provide two paths in par-

allel for the magnetic flux from one plunger to the other, one path having a relatively high permeance and the other being an interrupted shunt path of relatively low permeance, of an auxiliary armature arranged 70 to be actuated by the magnetic flux through the shunt path of the main armature, and means for developing a magneto-motive force to move the plungers in one direction.

2. The combination, with a pair of plungers, a yoke having openings to receive said plungers, and a main armature secured to both plungers and formed to provide two paths in parallel for the magnetic flux from one plunger to the other, one path having 80 a relatively high permeance and the other being an interrupted shunt path of relatively low permeance, of a strip-advancing mechanism arranged to be moved by the plungers, a strip-clamping mechanism carried by the strip-advancing mechanism and arranged to be actuated by the magnetic flux through the shunt path of the main armature, whereby the strip is clamped, and means for developing a magneto-motive 85 force to move the plungers in one direction.

3. In an electro-magnet device, the combination, with a pair of plungers, a yoke having openings to receive said plungers, and a main armature secured to both plungers and formed to provide two paths in parallel for the magnetic flux from one plunger to the other, one path having a relatively high permeance and the other being an interrupted shunt path of relatively low permeance, 100 the former path having a permeance less than that of the remainder of the magnetic circuit, of an auxiliary armature arranged to be actuated by the magnetic flux through the shunt path of the main armature, and means for developing a magneto-motive 105 force to move said plungers in one direction.

4. The combination, with a pair of plungers, a yoke having openings to receive said 110 plungers, and a main armature secured to both plungers, and arranged to provide two paths in parallel for the magnetic flux from one plunger to the other, one path having a relatively high permeance and the other being 115 an interrupted shunt path of relatively low permeance, of a strip-advancing mechanism arranged to be moved by the plungers and having a slot through which the strip may pass, a strip-clamping device of magnetic material having a central opening counter-bored on that side nearest the strip, 120 a pin carried by the strip-advancing mechanism and passing through said central opening, whereby said strip-clamping device tends to tilt against the strip, and means for 125 developing a magneto-motive force to move the plungers in one direction and also move the strip-clamping device to clamp the strip.

5. The combination, with a paper-shifter, 130

an electro-magnet device for operating the same, and a circuit including the electro-magnet device, of a relay arranged to close and open said circuit, a contact device operated by said electro-magnet device; arranged to close two circuits when said electro-magnet device is energized.

6. In a telautograph system, the combination, with a field magnet winding a power circuit in which said winding is included, 10 a pen lifter magnet winding, a pen lifting line circuit in which said pen-lifter winding is included, and a contact device arranged

to close both the power circuit and said pen lifting line circuit, of a writing line circuit, 15 a relay in said writing line, a paper-shifter, an electro-magnet for operating the same, a power circuit including the windings of said paper shifter electro-magnet and arranged to be controlled by said relay, said electro-magnet being arranged to control the contact device for closing the field magnet circuit and the pen lifter circuit.

In testimony whereof I have hereunto set my hand.

ARLEIGH NEIL VAN NOSTRAND.
